(57) **CLAIM**

The ornamental design for a mobile terminal with video display, as shown and described.

DESCRIPTION

FIG. 1 is a left side view of the mobile terminal with a video display of the present invention, wherein the mobile terminal is shown in an open position with a cover extending from a base of the mobile terminal.

FIG. 2 is a right side view of the mobile terminal with the cover in the open position.

FIG. 3 is a top plan view of the mobile terminal with the cover in the open position.

FIG. 4 is a bottom plan view of the mobile terminal with the cover in the open position.

FIG. 5 is a rear view of the mobile terminal with the cover in the open position; and,

FIG. 6 is a front view of the mobile terminal with the cover in the open position.
